UNITED STATES PATENT OFFICE.

EDWARD A. TRACY, OF BOSTON, MASSACHUSETTS.

ARCH-SUPPORT.

1,053,549.

Specification of Letters Patent. Patented Feb. 18, 1913.

Application filed March 18, 1909. Serial No. 484,264.

To all whom it may concern:

Be it known that I, EDWARD A. TRACY, a citizen of the United States, residing in Boston, in the county of Suffolk and State 5 of Massachusetts, have invented an Improvement in Arch-Supports, of which the following description, in connection with the accompanying drawings, is a specification, like reference characters on the drawings representing like parts.

The present invention relates to an arch support of the kind used in shoes, to support a broken down arch, in the case of so-called "flat-foot," the purpose of the invention being to improve the shape of the support so that it will more fully conform to the anatomy of the foot, and also to improve the construction and appearance of the support.

In the construction shown to illustrate the invention, the support is made with upper and lower members of leather which contain between them the spring which produces the general configuration of the support. In addition to the spring, I employ upper and lower supplementary pieces of leather which inclose the spring and project beyond the same, the said supplementary pieces being skived or otherwise varied in thickness, in order to produce the secondary configuration of the surface of the support. By this construction, a support is produced which has a slight depression in the higher portion of its surface, thereby conforming 35 to the shape of the foot at this portion, and preventing the tendency of the foot to slide downward laterally, as is the case with the arch supports constructed of the usual shape.

The lower spring inclosing member, furthermore, is carried forward of the spring, and slightly thickened at that point, thereby affording a support for the anterior arch which is not provided in arch supports as now made. It is not essential to the invention that the said forward support should be of the specific construction described, this feature of the invention consisting in providing the support with a yielding supporting portion flexibly connected with the main portion.

The several parts in the construction shown are joined together by cement, and also by means of a line of stitches around 55 the edges of the upper and lower leather

portions, these stitches also penetrating parts of the supplementary inner members so that all the parts are held in place by the stitches, as well as by the cement.

Figure 1 is a perspective view of an arch support embodying the invention, the inner parts being indicated by dotted lines; Fig. 2 is a longitudinal section through the same; and Fig. 3 is a transverse section.

The arch support is made up of upper 65 and lower members *a* and *b* of leather, one or both of which may be skived along the front edge, as indicated at *a*², Fig. 2 with respect to member *a*, and also along the inner edge, as indicated at *a*³, Fig. 3, so 70 that the completed support is thin at these points.

That portion of the support which is indicated at *a*³, Figs. 1 and 3, is bent upward, as shown, so as to fit in the inner side of 75 the shoe when the support is in place. The general configuration of the support is obtained by means of the spring *c* which also serves as a cushion, the said spring being located about in the middle of the support, 80 and projecting upward in the middle, as shown.

In addition to the spring, the supplemental portions *d* and *e* serve to inclose and 85 to cushion the spring, and also to produce minor variations in the shape of the supporting surface. The member *e* extends under the spring, and is carried forward beyond the front end of the spring in the form of an extension *e*² shaped substantially 90 off to different thicknesses as indicated at *e*³, Fig. 2.

The member *d* extends over the spring *c* projecting laterally beyond the same, as 95 shown in Figs. 1 and 3, the said member being skived, as indicated at *d*², so that the upper surface of the member *a* is caused to form a hollow *a*⁴ shown in Fig. 3, this hollow not only conforming better to the anatomy of the foot, but also constituting, in 100 a sense, an anchor which prevents the tendency of the foot to slip toward the outer side of the shoe.

The several parts are joined together by cement, and, in order to insure the permanency of the arrangement, the upper and lower surface parts *a* and *b* are joined along the edge by means of stitches *f*, these stitches also passing through the part *d* at 105 the portion *a*³ and through the projecting 110

portion e^2 of the part e . This insures the permanent location and maintenance of the support, even if the cement softens.

The forward support for the anterior arch has a yielding surface, preferably but not essentially provided for as hereinbefore described, and the main support and forward support are flexibly connected together.

10 Claims.

1. The herein described arch support for use in shoes, comprising essentially upper and lower members suitably united, a spring projecting upwardly in the middle, and upper and lower spring cushioning members between which the spring is inclosed, the said cushioning members being secured to each other around the spring and separately secured to and between the upper and lower members.

2. The herein described arch support for use in shoes, comprising essentially upper and lower members suitably united, a spring projecting upwardly in the middle, and upper and lower spring cushioning members 25 between which the spring is inclosed, the said cushioning members being secured to each other around the spring and separately secured to and between the upper and lower members, the upper and lower members having an upwardly extended flexible portion at one side and substantially opposite the upwardly projecting portion of the spring.

In testimony whereof, I have signed my name to this specification in the presence of 30 two subscribing witnesses.

EDWARD A. TRACY.
